DIAL PLATE FOR TIME SWITCHES

Frederick Otto Horsmann, Bath, England

Application September 12, 1952, Serial No. 309,309

Claims priority, application Great Britain

October 26, 1951

6 Claims. (Cl. 74—568)

This invention relates to time switches for controlling electric switches, gas valves and like switching devices. The invention comprises an improved dial plate having cam elements which can be readily attached to or detached from the dial plate and can be set in any desired positions to enable a switching device or devices to be actuated at desired times when the dial is rotated by a suitable time-regulated mechanism.

According to the invention, a dial plate for a time switch is constructed with an annular seating designed to support one or more detachable cam elements or segments in positions adjustable round the periphery of the dial plate, and has a clamping device by which any number of cam elements or segments can be clamped separately or in groups in adjusted position. Advantageously, the clamping device is constructed in the form of a ring or disc made with a plurality of springy clamping elements, each of which extends part way around the dial plate, and which together form a substantially complete ring by which a cam element or elements can be clamped in any desired position or positions round the dial plate.

The invention and its subsidiary features will be fully understood from the following more detailed description of a preferred construction of dial plate embodying the invention, which is illustrated by the accompanying drawings in which—

Figure 1 is a front view of the dial plate (one half being omitted for convenience of space);

Figure 2 is a section on line II—II of Figure 1;

Figure 3 is a sectional view of the front dial;

Figure 4 is a sectional view of the body disc taken on the line IV—IV of Figure 5;

Figure 5 is a face view of the body disc, looking from the right of Figure 4;

Figure 6 is a face view of a clamping device looking from the right of Figure 7;

Figure 7 is a sectional view of the clamping device taken on the line VII—VII of Figure 6;

Figure 8 shows a typical set of cam elements or segments;

Figure 9 is a side view looking from the left of Figure 8; and

Figure 10 is a perspective view of the left hand cam element of the set seen in Figure 8.

In the illustrated embodiment, the dial plate comprises a substantially flat body disc 1 (Figures 2, 4 and 5) adapted to be fixed by a clamping nut or other suitable means to a shaft (not shown) which passes through the central hole 2 and is adapted to be rotated by a clock or other time regulated mechanism. The time regulated mechanism may be a synchronous electric clock, a balance-regulated clockwork or any other mechanism designed to rotate the disc at constant speed related to graduations marked on the dial of the dial plate whereby the passage of time is indicated by the movement of the graduations relatively to an index as the dial plate rotates. The dial may be formed on one face of the body disc 1 or on a separate dial 3 attached thereto as illustrated. The dial plate is preferably designed to rotate once in seven days and may be divided as shown by means of markings on its outer face into segments each marked with the day of the week to which it corresponds and each having divisions for indicating the time of day.

A substantially annular clamping device in the form

2

of a back plate 4 (Figures 2, 6 and 7) fixed to the inner side of the body disc 1 has a peripheral portion 5 spaced away from the body disc 1 to allow cam elements or segments (Figures 8—10) to be inserted between the body disc 1 and the peripheral portion 5 of the back plate 4 and clamped therebetween. The peripheral portion 5 of the back plate is divided by radial slits 7 into a number of arcuate shape sections constituting independently movable clamping jaw plates, each of which extends part way round the body disc, and which together form a complete ring covering the whole of a continuous seating portion 13 which conveniently is a separate ring secured to the body disc as hereafter described. Each clamping jaw plate is controlled by a clamping nut or as shown, advantageously by a pair of clamping nuts 8 which can be tightened on angularly spaced screw pins 9 passing through holes 10 in the clamping jaw to cause the outer flanged edge 14 of the jaw to clamp one or more cam elements tightly against seating 13 on the rear face of the body disc. The clamping screws 9 are carried by the body disc as more clearly seen in Figure 4 and are radially inset from and clear of the seating 13 so that the cam elements can be set anywhere round the dial relative to the time graduations.

The jaw plates are conveniently of dish section, as shown, to provide the outer flanged arcuate edge 14 for engaging and pressing on the stems of the cam elements, and an inner flange 15 which engages the back face of the body disc 1 to space the jaw edge 14 therefrom so that a cam stem can be engaged thereunder and pressure can be exerted thereon by the clamping nuts 8. Advantageously, each clamping screw pin 9 carries a washer 16 between the body disc and the jaw plate so as to serve as a support spacer for the jaw.

The cam elements each may consist of a short length of metal or other material of substantially L-shaped as illustrated or T-shaped section, the tail portions 6 forming the stem of the L or T being adapted to enter the space between the springy jaw elements of the clamping devices constituted by the slit peripheral portion, and the seating 13 on the rear face of the body disc 1. The head portions 11 of the cam elements project radially from and engage the edge of the dial plate.

The cam elements, the heads 11 of which are adapted to actuate a tappet or tappets for operating a switch or switches, may be of various lengths corresponding to different intervals of time of for instance from one hour to say eight hours, so that a cam of any desired length can be built up by inserting a suitable number of cam elements in contiguous positions on the dial plate as in Figure 1. A number of cam elements having chamfered leading edges may be provided (see the right-hand pair in Figure 8), these elements being used to form a ramp at the leading end of each cam built up from one or a number of elements. The set illustrated in Figure 8 enable combinations to be set up giving periods of tappet operation of one to sixteen hours at hourly intervals. The chamfered elements are scribed with an indicating line 12 for setting against the dial graduations.

Advantageously, a felt, rubber or other compressible packing ring constitutes the seating 13 and is inserted in a circular groove provided for it in the rear face of the body disc 1. This compressible seating for the stems of the cam elements, enabling the pressure of the clamping jaws on the cam elements to be equalized when a number of such cam elements are held by a common clamping jaw.

The invention enables the dial plate to be set by inserting cam elements in appropriate positions thereon to move a switch or switches to "on" or "off" positions at any desired times during the period of one rotation of the dial plate. The cams can be adjusted to operate the switch

or switches either at the same times or at different times on different days of the week. To facilitate correct adjustment of the cam elements, the dial plate is preferably provided with clearly marked time divisions which extend to the circular edge of the time plate as in Figure 1. Correct setting of the cam elements can then be obtained by inserting the cam elements directly opposite the time divisions corresponding to the time intervals during which they are to operate.

Any cam element held by one jaw plate can be adjusted independently of other cam elements held by any of the other jaw plates, and can be set at any number of positions around the dial. Hence any program of switching not known at the time of manufacture of the mechanism, may be obtained and altered as and when desired. By virtue of the double clamping points on each jaw plate, effective securement of the cam elements during operation and when setting adjacent cam elements is possible.

A swivel handle 14 is preferably attached at the dial face of the dial plate.

I claim:

1. A dial plate for a time switch comprising a body disc having on one face time graduations dividing the periphery, cam elements each having an operating portion engaging the edge of the disc and angularly adjustable against said graduations, said cam elements being provided with stems projecting radially inwards over the opposite face of the disc, in combination with means on said opposite face for selectively securing with independent angular adjustment respective cam elements in an infinite number of positions relative to said graduations, said means comprising a continuous seating extending around the disc periphery under the respective cam stems, a plurality of independently movable clamping jaws of arcuate shape arranged in close juxtaposition so as to cover the whole of said seating, pressure applying members angularly spaced and inset radially from said seating, and connections between said jaws and said pressure applying members for moving the jaws so that they clamp the cam stems tightly against the seating.

2. A dial plate for a time switch comprising a body disc having on one face time graduations dividing the periphery, cam elements each having an operating portion engaging the edge of the disc and angularly adjustable against said graduations, said cam elements being provided with stems projecting radially inwards over the opposite face of the disc, in combination with means on said opposite face of the disc for selectively securing with independent angular adjustment said cam elements in an infinite number of positions relative to said graduations, said means comprising a continuous seating extending around the disc periphery under the respective cam stems, an annular back plate having a springy peripheral portion divided by angularly spaced radial slits extending from the outer edge inwards, into a plurality of independently movable clamping jaws covering said seating, and pressure applying clamps inset radially from said seating for securing and clamping the jaws against the seating with cam stems interposed therebetween.

3. A dial plate for a time switch comprising a body disc having on one face time graduations dividing the periphery, cam elements having an operating portion engaging the edge of the disc and angularly adjustable against said graduations, said cam elements being provided with stems projecting radially inwards over the opposite face of the disc, in combination with means on said opposite face of the disc for selectively securing with independent angular adjustment said cam elements in an infinite number of positions relative to said graduations, said means comprising a continuous seating extending around the disc periphery under the respective cam stems, an annular back plate having a springy peripheral portion divided by angularly spaced radial slits extending from the outer edge inwards, into a plurality

of independently movable clamping jaws covering said seating, said peripheral portion having a plurality of angularly spaced holes disposed one adjacent to and on each side of each slit, a plurality of pins inset radially from the seating and projecting from the body disc in corresponding angular positions to those of the holes with the holes engaged thereover, spacing means holding the jaws spaced from the body disc, and a clamping nut on each of said pins to press the jaws into clamping engagement with the seating.

4. A dial plate for a time switch comprising a body disc having on one face time graduations dividing the periphery, cam elements having an operating portion engaging the edge of the disc and angularly adjustable against said graduations, said cam elements being provided with stems projecting radially inwards over the opposite face of the disc, in combination with means on said opposite face of the disc for selectively securing with independent angular adjustment said cam elements in an infinite number of positions relative to said graduations, said means comprising a seating ring secured around the disc periphery under the respective cam stems, an annular back plate having a springy peripheral portion of dish shape cross section covering the seating, and divided by a plurality of angularly spaced radial slits extending from the outer edge inwards, into a plurality of independently movable jaw plates of which the inner arcuate edge engages the disc face and the outer arcuate edge lies over the seating to engage the cam stems, said peripheral portions having a plurality of angularly spaced holes disposed one adjacent to and on each side of each slit, a plurality of pins inset radially from the seating and projecting from the body disc in corresponding positions to those of the holes with the holes engaged thereover, and a clamping nut on each of said pins.

5. A dial plate according to claim 4, wherein on each pin is provided a washer which lies between the related jaw plate and the body disc and is of a thickness to hold the outer arcuate edge of the jaw plate spaced from the seating to grip a cam stem placed therebetween when the clamping nut is screwed down.

6. A dial plate for a time switch comprising a body disc having on one face time graduations dividing the periphery, cam elements each having an operating portion engaging the edge of the disc and angularly adjustable against said graduations, said cam elements being provided with stems projecting radially inwards over the opposite face of the disc, in combination with means on said opposite face for selectively securing with independent angular adjustment respective cam elements in an infinite number of positions relative to said graduations, said means comprising a continuous seating extending around the disc periphery under the respective cam stems, a plurality of independently movable clamping jaws of arcuate shape arranged in close juxtaposition so as to cover the whole of said seating, each of said jaws consisting of a springy plate having between inner and outer peripheral edges angularly spaced holes which engage over correspondingly spaced pins projecting from the body disc in positions radially inwards of the seating, a cam engaging flange on the outer peripheral edge of said jaw plate, spacing means holding said jaw plate spaced from said disc so that a cam stem can be engaged between the flange and the seating, and a clamping nut on each of said pins.
